[57] ABSTRACT

A cupola for melting pig iron or steel scrap. The cupola has a belly having a tapping hole at the lower portion thereof, a plurality of more than two spiral combustion chambers provided outside of belly burners. The burners use creosote oil as fuel and direct flame into these combustion chambers. The combustion chambers are provided with tuyeres for blowing flame from the burners into the belly, and the space under the belly is filled with a large number of block-shaped elements of refractory material having a high degree of refractoriness.

CUPOLA

The present invention relates to a cupola for melting pig iron or steel scrap, particularly to a cupola using heavy oil.

A conventional cupola burns cokes to melt pig iron or steel scrap. With such a method, as the hearth is filled with bed cokes thereon and hot air is blown in from the tuyere to burn cokes to melt pig iron, the quantity of the cokes depends upon the size of the belly and the charging quantity of pig iron or steel scrap also depends upon the quantity of the cokes, the melting capacity of cupola can not be varied freely. And after every finish of operation, the hearth is to be opened, and remaining cokes and metal after burning must be taken out, and also the operation can not be restarted without repairing and drying the hearth removed therewith, so the efficiency of operation is low. Moreover, as cokes contain much sulphur, exhaust gas contains much sulphuric dioxide gas and also much soot, there is a defect to expend much cost for removing them.

The first object of this invention is to provide a cupola feasible to eliminate such a defect of existing cupola as above described, operable continuously and able to reduce melting cost by using heavy oil and block refractory material.

The second object of this invention is to provide a cupola operable automatically with usage of heavy oil, particularly creosote oil.

The third object of this invention is to provide a cupola creating little sulphuric dioxide and soot while producing pig iron of excellent quality by using creosote oil. These and other objects may be accomplished by improvement, combination and operation of each portion constructing this invention and embodiment thereof will be clear from the accompanying drawing and the detailed explanation described later. And, revision or modification with respect to details of the construction is to be included in the claim described later.

FIG. 1 is a front view partially sectioned, showing an embodiment of the cupola according to this invention.

FIG. 2 is a cross section on line 2—2 in FIG. 1.

FIG. 3 is a cross sectional plan on line 3—3 in FIG. 1.

The cupola according to this invention comprises a chimney 13 having a belly 11 and a dust arrester 12. The hearth 14 of the belly 11 is slightly slant, a plurality of tapping ports 15 are formed below the belly 11 at the lower portion of the hearth. In front of the tapping ports 15 is provided a slag separating trough 16, under the front end of this slag separating trough 16 is located the fore hearth 17.

On the periphery of said belly 11 is formed the combustion chamber 18. The plan of this combustion chamber 18 is as shown in FIG. 2, at a portion thereof is disposed tangentially the burner fixture 19, a burner 20 for burning the creosote oil heated at 50°-80° C. is provided on the burner fixture 19. In FIG. 2, the burner fixture 19 is only one, but another burner fixture 19 may be added as shown with a dot-and-dash line in FIG. 2, and a burner 20 may be disposed on each burner fixture 19. And also, in the belly 11 within the combustion chamber 18 are provided a plurality of tuyeres.

Above the combustion chamber 18 is provided the upper combustion chamber 22 surrounding the

periphery of the belly 11. Each of the combustion chambers 22 of spiral is disposed at two places as shown in FIG. 3, and each combustion chamber 22 is provided respectively with the burner 23 for burning the creosote oil heated at 50°-80° C. similarly with the above description, and in the belly 11 forming the inner side of the combustion chamber 22 is provided the tuyeres 24 communicating the interior of the belly 11 and the combustion chamber 22. There are provided two combustion chambers and two burners respectively in the illustrated embodiment, they may be more than three respectively.

To the upper portion of the belly 11 is connected the heat absorbing tube 25 made with steel plate and the like and the outside thereof is encircled with the air preheating chamber 26. This air preheating chamber 26 is connected with the blast pipe 28 to the discharge opening of the blower 27 disposed at the side thereof. And, in the intermediate of the blast pipe 28 is provided the damper 29 to regulate the quantity of blast. The lower portion of the preheating chamber 26 and said combustion chamber 18, 22 are interconnected with plural tertiary air pipes having stop valves 30 in the intermediate thereof respectively, the air from the blower 27 hugs the heat absorbing tube 25 within the preheating chamber 26 to be heated for making tertiary air of high temperature, and when required it is to be sent to each combustion chamber 18, 22.

Furthermore, to said preheating chamber 26 is also connected the secondary air pipe 38, and this pipe 38 is connected to the secondary air port of each burner 20, 23. Namely, each burner 20, 23 spouts mixture of fuel and air with the primary air of high pressure from the compressor and blows into the combustion chamber 15 or 22 the mixture on burning it by mixing with the secondary air comprising a large quantity of compressed air of lower pressure from the pipe 38. And, in the outer wall of the combustion chamber 22 is disposed the firing port 39, but the firing port 39 is closed during burning.

Above said heat absorbing tube 25 is disposed the charging hopper 32. On this charging hopper 32 is projected the lower opening of the charging chute 33, on the charging rail 34 arranged between this charging chute 33 and the floor is mounted movably up-and-down the charging bucket 36 hangable with the hoist 35 located at the upper portion thereof, and with this bucket 36, pig iron, steel scrap and the like are to be charged into the belly 11.

37 is a plurality of refractory materials of block shape filled from the hearth 14 within the belly up to the middle portion of the upper combustion chamber 22. These refractory materials are blocks made with silicon carbide or primary burned carbon having refractoriness of high degree.

Pig iron, steel scrap, limestone and other desired elements of a proper rate are charged on said refractory materials 37 with said bucket 36, and when the blower 27 is started while opening the damper 29 properly and each burner 20, 23 is started to burn, the flame created by each burner 20, 23 is flown into the belly 11 from each tuyere 21, 24 while whirling within each combustion chamber 18, 22, is risen while red-heating the refractory materials, heats the pig iron and steel scrap on the refractory materials, is further risen through the

heat absorbing tube 25 and then is exhausted from the chimney 13. And, the air of high temperature from the preheating chamber 26 is sent to each burner 20, 23 through the secondary air pipe 38 and helps the burner 20, 23 burn, but when the quantity of oil spouted from the burners 20, 23 is increased and the quantity of air is short with respect to fuel, the valve 30 is to be opened to send a large quantity of tertiary air of high temperature from each tertiary air pipe 31 into each combustion chamber 18, 22 to assist burning. Namely, when the quantity of steel scrap and pig iron to be melted is small, the valve 30 is closed and the cupola is operated on stopping supply of tertiary air, and when the quantity of steel scrap and pig iron is large, then the valve 30 is opened and a large mass of fuel is to be burned. The point wherein the quantity to be melted is changeable freely is also a feature of this invention.

The pig iron and steel scrap on the refractory materials 37 is melted by the operation above mentioned, stored on the hearth 14 through the space between the refractory materials 37, enters the separating trough 16 from the tapping port 15 and then is poured into the fore hearth 7 after separation of floating slag.

NUMERAL VALUE OF THE EMBODIMENT

1. blower (turbo blower)	
static wind pressure	700 mm
driving motor	7 1/2 HP
blast volume	25 m ³ /min.
No. of revolution	3,600 R.P.M.
diameter of blast pipe	50 mm ϕ
2. charging machine (bucket-type automatic charging device)	
with 1 HP hoist motor	
charging rate	50 kg/ a time
conveyed to the bucket with magnetic crane.	
3. furnace	
diameter	400 mm (with upper preheating chamber)
total height	3,500 mm
burner	40 l/h 3 for spouting oil
combustion chamber	two stages
firing port	3
tapping hole	2
(with slag separating trough)	
fore hearth	150 kg/a time 1 set
secondary air pipe	75 mm ϕ 3 (with sluice valve)
tertiary air pipe	28mm ϕ 3 (with stop valve)
4. fuel (creosote oil No. 1 – No. 4)	
calorie	11,000 – 12,000 calories
No. 1, No. 2	9,500 – 10,000 calories
No. 3, No. 4	below 0.2%
water	

sulphur	below 0.2%
specific gravity	1.071

Said creosote oil is supplied to the burner after heating up to 50° – 80° C. with a heat exchanger using water heated up to 100° C. with an electric heater of 1 Kw/h.

5	5. Air compressor for supplying primary air for spouting fuel to the burner.
10	driving motor 15 HP
	spouting quantity 2,280 l/min.
	Capacity of main tank 0.28 m ³
	pressure 6 Kg/cm ³ – 8.5 Kg/cm ³
15	working pressure in tank 5 Kg/cm ²
20	6. burner for drying the fore hearth 1 proportion of material
	Charging quantity per a time (for example) FC – 20 – 22
	New pig iron (No. 1 of S.S.K.) 15Kg
	Used pig iron (returned pig iron) 20Kg
	scrap (steel scrap) 15 Kg
	limestone 1 Kg
	ferrosilicon 0.4 Kg
	ferro manganese 0.4 Kg
	refractory material (silicon carbon or primary burned carbon) 70 Kg

In the case above mentioned, the molten metal is at 1,500° C. and has excellent fluidity, carbonization and decarbonization may be regulated freely.

25 And also, molten metal tapping quantity is 1,160 Kg/h., as in the case of conventional diameter of 400 mm ϕ (the diameter of the tuyere of furnace), the molten metal tapping quantity is 500 Kg/h, it is clear that 30 the cupola according to this invention has a capacity larger than two times.

We claim:

1. A cupola comprising a belly having tapping hole at the lower portion thereof, plural spiral combustion 35 chambers provided outside of the belly burners more than two using creosote oil as their fuel for spouting flame into these combustion chambers, and the combustion chambers are provided with tuyeres for blowing flame from the burners into the belly, and under the 40 belly are filled with a large number of refractory materials of block-shape having refractoriness of high degree.

2. A cupola as claimed in claim 1 wherein a preheating chamber is provided at the upper belly, which preheats the air supplied from a blast member, and this 45 preheating chamber and each combustion chamber are interconnected with secondary air pipe.
